CLAIM

The ornamental design for a golf club shaft, as shown and described.

DESCRIPTION

FIG. 1 is a right side elevational view of a golf club shaft showing my new design, the undisclosed opposite side being identical;

FIG. 2 is a front elevational view of the invention illustrated in FIG. 1; and.

FIG. 3 is a top plan view of the invention illustrated in FIG. 1.

The broken line showing of the handle and golf club head is for illustrative purposes only and forms no part of the claimed design.
